UNITED STATES PATENT OFFICE

2,612,662

WINDOW STRUCTURE

William M. Pfaff, Braddock, Pa., assignor to
Standard Aluminum Products Company, Brad-
dock, Pa., a corporation of Pennsylvania

Application February 25, 1950, Serial No. 146,249

1 Claim. (CL 20--55)

1

My invention relates to storm windows or supplementary windows of the casement type, and is here shown as comprising a master frame that includes glazed, hinged storm sash nesting in the frame, the frame being permanently attached to the exterior faces of various types or designs of standard or special out-swinging casement windows, whereby to secure the advantages of a double glazed window.

One object of my invention is to provide a storm sash that need not be removed for ventilation, cleaning or the installation of interior screens, the arrangement having the further advantage of being especially suitable for air-conditioned buildings, because of the dead air space.

My improved structure has further advantages, such as minimizing sweating and the leakage of air and dirt, and the use of a semi-liquid sealing compound between my master frame and the casement windows to which the frame is applied, prevents rust or corrosion between the metal-to-metal surfaces, and serves as a water-proof seal.

While the invention is described more particularly as applied to an already-installed casement window, obviously my storm window can be applied to a casement window frame at the factory and the complete combination shipped and installed as a unit.

As shown in the accompanying drawings, Figure 1 is an outer face view of my storm window; Fig. 2 is a perspective view thereof, on a reduced scale, showing the storm windows in open position, at the outer face of the casement window structure; Fig. 3 is a view taken on the line III--III of Fig. 2; Figs. 4, 5, 6 and 7 are views taken on the lines IV--IV, V--V, VI--VI and VII--VII respectively of Fig. 1, on enlarged scales; Fig. 8 shows a modification wherein the transom of the structure of Figs. 4 and 5 is omitted; Fig. 9 is an enlarged face view of an upper portion of the structure of Fig. 1, below the transom of Figs. 1 and 5; Fig. 10 is a view taken on the line X--X of Fig. 9; Fig. 11 is a view on an enlarged scale of the lower right-hand corner of Fig. 1; Fig. 12 is a view taken on the line XII--XII of Fig. 11; Fig. 13 is a view taken on the line XIII--XIII of Fig. 11; Fig. 14 is a side view of one of the reinforcing angles of Figs. 9 and 10; Fig. 15 is an edge view thereof; Fig. 16 is a face view of a standard casement window before installation of my storm window thereon; Fig. 17 is a face view of a standard hinged casement sash frame employed in conjunction with the frame of Fig. 16 and Fig. 18 is an enlarged plan view of one of the hinges of Figs. 2 and 11.

2

The sash frames of Figs. 16 and 17 may suitably be of steel or aluminum and when assembled, will fit a window opening of standard form. The large frame 19 comprises stile members 20, a lintel member 21, a bottom bar 22, a mullion bar 23 and a cross bar 24. Sash bars 25 are connected across the stile 20 and the mullion bar 23, and panes 26 are set into the frame thus formed, these being the inner panes of the window. Similarly, the auxiliary sash frame 28 of Fig. 17 has stile members 29 and cross bars 30, 31, 32 and 33 in which are mounted glass panes 34. This auxiliary frame 28 is hinged at 35 to one of the stiles 20, so that it can be swung outwardly from the position shown in Fig. 7 to the position shown in Figs. 2, 3 and 11.

A transom window comprises a frame 37 (Fig. 4) that is rigidly connected to the lintel bar 21 and the stiles 20, as by screws 38. This sash frame 37 has a swinging sash 39 hingedly connected thereto at 41 and carries panes of glass 42. Transom panes 43 are mounted in the members 20, 21, 23 and 24 of Fig. 16.

Springy flashing strips 44 are provided for the upper and lower edges of the transom, and flashing strips 45 and 46 extend downwardly along the vertical edges of the transom as shown in Fig. 6, the strip 45 extending clear to the bottom of the window while the strip 46 terminates at the lower edge of the transom. Below the strip 46, a sealing angle 47 is provided as shown in Figs. 7 and 1.

A swinging storm sash 48 (Figs. 2, 5 and 7) is hingedly connected at 49 to a storm window frame 50 that is secured by screws 50a to the left-hand stile 20 of the sash frame 19. An outer window pane 51 is mounted in this frame 48 between a rubber strip 52 and a spring spline 53, as shown in Fig. 7 and on a larger scale with the pane of Fig. 13. The sash 48 will swing open on the frame 50 as indicated in Figs. 2 and 3.

The auxiliary sash frame 28 has a sash frame 54 connected thereto by screws 55, and these members are hingedly connected at 35 to the right hand rigid frame stile 20 in accordance with standard practice, as shown more clearly in Figs. 11, 13 and 18. A swinging storm sash 56 is hingedly connected at 57 to the frame 54.

Flashing strips 58 are provided for the lower edge of the window, to bear against the sill, and at the upper edge of the frame of Fig. 8.

Stiffening angles 59 and 60 are provided in the corners of the frame structure, the angle 59 having drive fit with the frame members 37 and the angle 60 having drive fit with the sash members 39, as shown more clearly in Figs. 9 and 10.

When it is desired to open the windows for ventilation or for cleaning, a crank 63 is turned to swing the frame 28 outwardly, in a manner well known in the art, thus opening the window frame 28. Also, the swinging sash frame 56 can then be swung on its hinges 57, to bring the parts to approximately the positions shown in Figs. 2 and 3.

As shown in Fig. 18, the hinge arms 35a and 35b that are secured to the frame members 20 and 29 respectively have their pivotal point of connection set perpendicularly outward from the face of the window, so that when the frame 28—29 is swung to the dotted line position of Fig. 18, there will be a space left at 65 (Fig. 2) through which the user may extend his arm. Both sides of the panes 34 and the panes 64 in the sash 56 will then be accessible for cleaning. Also, the cleaner can reach to the outer face of the glass 26 and to the inner face of the glass 51, to clean them. Of course, when the glass 51 is closed, the outer face thereof is clearly accessible by one reaching outwardly through the opening across which the frame 28 is hung.

Spring clips 66 are provided at various points throughout the structure, as shown more clearly on Figs. 1 and 7, to hold the swinging panels snugly against their frame members when the windows are closed. Also, non-hardenable adhesive or mastic is provided at various points where there is ordinarily fixed metal-to-metal engagement between the parts, as shown at 67 in various of the figures, such as in Figs. 18, 4 and 6. Suitable latching devices will be provided as indicated at 68.

It will, of course, be understood that the sash frame members of Figs. 16 and 17 may be of steel, aluminum, wood or other suitable materials. Where aluminum is employed in the structure, as for example in the case of the frames 28, 37 and 54, the interposition of the mastic 67 between the aluminum and the steel members protects the aluminum against corrosion as well as preventing

air leaks and condensation of moisture. It will also be seen that there is but limited direct path for conduction of cold or heat through the metal members, as will be apparent in viewing Figs. 7 and 18 for example, wherein although inner and outer metal members have direct contact except for the mastic, there are staggered air spaces.

In Fig. 8, a slightly different form of window structure is shown. The principal difference between this and the other structures is that the transom is omitted, that portion of the frame 19 above the bar 24 being cut away. In this arrangement, the auxiliary sash frame 28 and its swinging storm sash will be mounted in the same manner as in the other figures and the frame 50 for the swinging sash 48 similarly mounted.

I claim as my invention:

A window structure comprising a main casement frame installed alongside a fixed closure means of extended area, an auxiliary sash frame hinged at one edge to the main frame, by a pair of hinge leaves which extend perpendicularly from the planes of the frames and are pivotally connected at their outer ends, and are of such length that when the auxiliary sash frame is swung from a normal position of parallelism with respect to the main frame, the adjacent hinged edges of the frames become separated for a distance sufficient to permit an operator to extend his arm to the exterior of the window, and a storm window sash hingedly connected to the auxiliary sash frame at the free edge of the auxiliary sash frame and being movable thereon, to form a double-paned window structure.
